UNITED STATES PATENT OFFICE

WILLIAM M. SHEEHAN, OF MERION, PENNSYLVANIA, ASSIGNOR TO GENERAL STEEL CASTINGS CORPORATION, OF GRANITE CITY, ILLINOIS, A CORPORATION OF DELAWARE

CENTER PLATE STRUCTURE

Application filed May 11, 1931. Serial No. 536,602.

The invention relates to railway rolling stock and consists in a novel center plate and associated structure for vehicles underframes and particularly for railway tenders, tank cars, etc., in which the underframe forms the bottom of a tank structure.

In previous water bottom tender frames, it has been the practice to apply separate center plates with either rivets or bolts and, 10 in order to obviate the necessity of piercing the tank bottom forming web plate, there have been provided bolting flanges spaced a short distance below the web plate. This has resulted in weakening the center plate 15 structure and in raising the adjacent portion of bottom of the tank and consequently decreasing the tank capacity.

Center plates have also been cast integral with the underframe, but this construction 20 makes machining more difficult than if the center plate is formed separately and secured to the underframe after machining.

The main object of the present invention is to provide a separately formed center plate 25 structure which may be welded to the underframe after machining and which will afford maximum strength and tank capacity. I attain this general object and others, later appearing, in the structure illustrated in the accompanying drawings in which—

Figure 1 is a top view of the forward half of a tender underframe embodying my invention.

Figure 2 is a vertical longitudinal section 25 taken on line 2—2 of Figure 1.

Figure 3 is a vertical transverse section taken on line 3—3 of Figure 1.

Figure 4 is a detail horizontal section taken on line 4—4 of Figure 2.

In Figure 1 is shown a portion of a one-piece water bottom tender underframe including side sills 1, intermediate longitudinal sills 2, center sills 3 and 4, end sill 5, transoms 6 and 9, including vertical webs 7 and 8, and bolster 14. An imperforate horizontal web 10 extends the length and breadth of the casting, merging with the webs of the sills, transoms, and bolsters, and forms the tank bottom. Formed integrally with the end sill 5 is a pocket 11 for a spring buffering

device and pockets 12 and 13 for a drawbar and a safety bar, respectively. All of the above structure is old and in itself constitutes no part of the present invention.

Bolster 14, extending from side to side of the underframe merges with side sills 1, as at 15, and has a central deepened portion 16 for receiving the body center plate 27 which bears directly against the truck center plate (not shown). Center sills 3 and 4 and bolster webs 60 7 and 8 form a box at their intersection with in this depressed portion, as shown in Figure 4, and transverse webs 17 and 18, transverse ribs 19 and 20, and longitudinal ribs 21 and 22 serve to strengthen the structure above the 65 center plate. Vertical ribs 23 and 24 extend between webs 17 and 18 and webs 7 and 8, respectively, and a horizontal web 25 assist in maintaining the rigidity of the reinforcing structure. 70

A substantially cylindrical recess 26 is formed in the bottom plate of the bolster for receiving a cylindrical dowel 29 projecting from the upper surface of the center plate 27 which also has the usual recess 28 in its lower 75 surface for receiving a corresponding projection on the truck center plate. The dowel 29 and the co-operating recess 28 need not necessarily be cylindrical but may be of any suitable shape. The center plate 27 is applied 80 to the frame by inserting dowel 29 into recess 28 and welding the plate to a boss 30 surrounding this recess as shown at W. Dowel 29 serves to maintain the parts in alignment 85 during welding and to relieve the weld of horizontal forces set up between the truck and the underframe during the movement of the vehicle.

By this construction, the body center plate 90 may be conveniently machined separately from the underframe and when the center plate and underframe are assembled, the underframe will be positioned substantially lower than would be the case if bolting flanges 95 depending from the bolster bottom web and the connection between truck and underframe will be substantially stronger.

The invention is obviously not limited to the exact construction of the selected embodiment shown and described, but may be modi- 100

fied as to various details without departing from the spirit of the invention and I contemplate the exclusive use of all such variations as come within the scope of my claims.

I claim:

5. 1. A railway vehicle underframe including a bolster having a recess in the lower surface thereof, and a body center plate welded to said bolster and having an upwardly projecting dowel inserted into said recess to hold the parts in alignment. 70
10. 2. In combination, a railway vehicle bolster having a recess in the lower surface thereof and having a boss adjacent said recess, and a center plate having a dowel projecting upwardly therefrom and inserted into said recess to hold the parts in alignment, said center plate being welded to said boss. 75
15. 3. In a railway vehicle a bolster having reinforcing ribs above the center portion thereof and a recess in its lower surface beneath said ribs, and a center plate welded to said bolster and having an upwardly projecting dowel inserted into said recess to hold the parts in alignment. 80
20. 4. In a railway vehicle, a bolster having reinforcing ribs above the center portion thereof and a recess in its lower surface beneath said ribs, a boss adjacent said recess, and a center plate having an upwardly projecting dowel inserted into said recess to hold the parts in alignment, said center plate being welded to said boss. 85
25. 5. In a railway vehicle underframe, spaced center sills, a bolster intersecting said sills and having a deepened central portion between said sills, and having a horizontal web forming part of a tank bottom, a recess in said web, and a center plate welded to said web and having a dowel projecting upwardly into said recess to hold the parts in alignment. 90
30. 6. In a railway vehicle underframe, spaced center sills, a bolster intersecting said sills and having a deepened central portion between said sills having a bottom web forming part of a tank bottom, a recess in said web, reinforcing ribs in said deepened portion, and a center plate welded to said web and having a dowel projecting upwardly therefrom and inserted into said recess to hold the parts in alignment. 95
35. 7. In a railway vehicle, an underframe member, and a center plate welded to said member, there being elements on said member and center plate having substantially vertical engaging surfaces to relieve the weld of horizontal forces arising from operation of the vehicle. 100
40. 8. A railway tank vehicle underframe having a web forming the tank bottom, a bolster above said web, said web having an imperforate recess beneath said bolster, and a center plate welded to said bolster and having a portion fitting into said recess. 105
45. 9. A railway vehicle bolster having vertical and horizontal webs forming a box structure at the center of the bolster, the lower horizontal web being recessed upwardly between said vertical webs to receive a center plate dowel, there being vertical reinforcing ribs extending between pairs of said vertical webs and traversing the recessed portion of said horizontal lower web. 110
50. 10. A railway vehicle underframe including a bolster and a body center plate welded to said bolster, said bolster and center plate having interengaging elements to hold the parts in alignment independently of the welded joint. 115
55. 11. In combination, a railway vehicle bolster having a boss on its lower surface, and a center plate welded to said boss, said bolster and center plate having interengaging elements to hold the parts in alignment independently of the welded joint. 120
60. 12. In a railway vehicle, a bolster having reinforcing ribs above the center portion thereof, and a center plate welded to said bolster, said bolster and center plate having interengaging elements to hold the parts in alignment independently of the welded joint. 125
65. 13. A railway vehicle underframe including a bolster member and a body center plate member welded to said bolster member, one of said members having a recess and the other of said members having a dowel adapted to be inserted into said recess to hold the parts in alignment independently of the welded joint. 130
70. 14. A railway tank vehicle underframe having a web forming the bottom of the tank, and a center plate welded to the underside of said web, there being interengaging elements on said web and center plate to hold the parts in alignment independently of the welded joint. 135
75. 15. In a railway vehicle underframe, a substantially horizontal bottom web having a recessed portion for receiving a complementary member on a body center plate, and a reinforcing structure above said recess and including longitudinal and transverse webs forming a box, and vertical longitudinal ribs entirely traversing said box and intersecting said recessed portion. 140
80. In testimony whereof I hereunto affix my signature this 4th day of May, 1931. 145
85. WILLIAM M. SHEEHAN. 150
